PICKER STOP

George F. Belforti, Milford, Mass., assignor to
Draper Corporation, Hopedale, Mass., a corpora-
tion of Maine

Application January 5, 1942, Serial No. 425,588

5 Claims. (Cl. 139—161)

This invention relates to an adjustable means for stopping the travel of a picker in a predetermined position.

In a filling replenishing loom where reserve filling carriers automatically are taken from a magazine and placed in the shuttle upon exhaustion of the filling from the carrier presently in the shuttle, it is necessary that the shuttle be accurately positioned for the replenishing operation properly to be accomplished. The shuttle must be stopped in a position directly beneath the magazine so that the new filling carrier can be forced into the holding means provided in the shuttle and the old filling carrier ejected therefrom.

On coming into the shuttle box, the shuttle contacts the picker and forces it, and the picker stick, outwardly. It is usual to provide a stopping means at the outer end of the lay to check the travel of the picker stick, and hence also the travel of the picker attached to it. A common means for accomplishing this is the use of a loop of leather placed on the lay to abut the shank of the picker stick. Such a means lacks ready adjustability.

It has also been proposed to make stopping devices with some degree of adjustability so that the position in which the picker stick would be stopped could be varied, but these prior devices were objectionable in that they required a modification of the lay end to adapt it to receive them, or were comparatively complicated in construction and operation, or lacked sufficient strength to remain in operative position under the forces encountered in modern high speed looms.

Another objection found in such prior devices is that they are made to contact the picker stick along its shank to check its travel. In such a situation, when the motion of the picker stick is checked abruptly, the tip of the stick will tend to bend and whip, using the stop as a pivot point, and cause the shuttle to rebound out of its proper position.

It is an object of this invention to provide for a picker an adjustable stopping device which readily can be applied to a loom without alteration of existing parts and which will remain in adjustment to stop the picker in a predetermined position during the continuous operation of a high speed loom.

These and other objects may be attained by the construction shown, as an exemplary embodiment of my invention, in the drawing, in which:

Fig. 1 represents a portion of the replenishing side of a loom with my invention applied to the end of the lay; taken from the front of the loom.

Fig. 2 represents a portion of the lay end shown in Fig. 1, to an enlarged scale, taken from the rear of the loom, and shows the cooperative relationship between the picker and the stopping device.

Fig. 3 shows a perspective view of a device made according to my invention with the parts disassembled.

The portions of the loom shown comprise a loom side 1 having a magazine 2 attached thereto. The magazine holds a plurality of filling carriers, one of which is shown at 3 in a position ready for transfer to a shuttle 4. The shuttle is momentarily at rest in a shuttle box 5 on the end of the lay 6.

In this position the spur 7 of the shuttle engages the picker 8, which is attached to the picker stick 9. Therefore the position of the picker will determine the position of the shuttle.

In order to control the position of the picker, I have provided a stop means 10 secured to the end of the lay 6.

The stop means comprises a body member 11 made of metal, or the like, of sufficient strength to withstand the stresses imposed on it by the constant pounding of the picker. It has formed in it two slots 12 and 13, one of which is disposed approximately parallel with the longitudinal axis of the member, and the other of which intersects the longitudinal axis at an angle of approximately forty five degrees. The exact disposition of the slots is not controlling in the proper functioning of my invention if they meet the requirements set forth subsequently.

One end portion of the body member 11 has formed therein an opening 14 to receive a stud 15. The stud is attached to a part 16 which comprises a core 17 about which is wrapped a resilient material, such as leather, or the like, 18. The resilient material may be fastened to the core member by screws 19, passing through the resilient material and screw threaded into the core.

In assembling, the stud is placed through the opening 14, a lock washer 20 placed over the protruding end thereof, and a nut 21 threaded thereon to hold the elements in place.

The stop means is attached to the loom by bolts 22 passed through the slots 12 and 13 and screw threaded into appropriate holes formed in a face of the end of the lay 6. It is so placed that the part 16, will project over the top of the lay and into the path of travel of the picker 8.

The slots 12 and 13 are arranged in the body member 11 so that they permit vertical and longitudinal adjustment of the position of the

projecting part 16. They also are so disposed that the center 23 of the part 16 can be caused to be moved in a straight line parallel with the top surface of the lay.

In adjusting the stop member in working position, the part 16 is placed so that the bottom of the resilient material 18 rests on the top surface of the lay, as at 24, and a flat face of the resilient material 18 lies flush with the end face of the picker, as at 25. In this position the force of the picker on contacting the stop means is distributed throughout the full area of the abutting faces, and a concentration of high stresses over a small area is prevented. Also, the stop member contacts the picker at a point directly in line with the direction of the force of impact imposed on the picker by the shuttle, and rebound of the shuttle due to bending of the picker stick is prevented.

By causing the projecting member 16 to rest on the top of the lay, the device is made more rigid than it otherwise would be.

All of these adjustments are made possible by the disposition of the slots 12 and 13 and by the revoluble nature of the connection between the part 16 and the body member 11. The range of adjustment is indicated by the full lines 8, and 16, and the dotted lines 8', and 16' in Fig. 2.

To find the correct position for the stop means, the shuttle is placed under the magazine in the proper position for a transfer. The picker is moved to engage the spur of the shuttle in close contact. With the bolts 22 and the nut 21 in a loosened condition, the stop means is moved until the various parts abut each other in the manner described above. The bolts 22 and the nut 21 are then tightened to place the stop means in operative condition.

In operation, the stop means will abut the picker on its outward stroke to cause it to stop in the predetermined position. Since the shuttle is in contact with the picker during the latter part of its outward stroke, the shuttle also will be stopped in the desired position. If wear on the parts causes the elements to become out of adjustment, readjustment is easily and readily made by performing the adjusting operations set forth above.

Having thus described a preferred modification of my invention, I claim:

1. In a loom, a means for stopping a picker in a predetermined position comprising an element having an end of said element extending above the lay of said loom, means for adjustably attaching said element to a portion of said loom, and a member adjustably attached to the said

end of said element in position to rest upon the top surface of said lay and to bear thereagainst when engaged by the picker at a predetermined point of its travel.

5. 2. In a loom, a picker stopping device comprising a member arranged to be adjustably secured to the front face of an end of a lay, a portion of said member extending above the top of said end of said lay, and a stop member adjustably fixed to the said portion of said first member and arranged to be positioned to engage the top surface of said lay and to abut the said picker at the extreme outward terminus of its travel.

3. In a loom, a means for stopping a picker stick in a predetermined position, comprising an element arranged to be placed in the path of travel of said picker stick, said element having means incorporated therewith to pivotally secure it in adjusted position to an arm, said arm having means formed therein to permit it to be adjustably secured to a face of a lay and to permit said element to rest upon said lay and to bear thereagainst when said element is engaged by the picker as the picker approaches the outer limit of its movement.

4. In a loom, a picker stopping device comprising a member having slots therein by which said device can be adjustably secured to an end of a lay, said member having a portion thereof extending above the top of said lay, a stop member extending into the path of travel of the picker and adjustably connected to said extended portion of said first member, and means for rigidly securing said stop member in adjusted position in engagement with the top surface of said lay, whereby said stop member can be adjusted in position to stop the picker at a predetermined point of its travel.

5. In a loom, a means for stopping a picker at a predetermined point of its travel comprising a member arranged to be placed in the path of travel of said picker, said member being angularly adjustable to enable it to be placed in a position parallel with a face of said picker, said member being secured to an arm, said arm having slots therein through which means may be passed to secure said arm to a face of the lay of said loom, said slots being arranged to enable said arm to be adjusted in a vertical and a longitudinal position relative to said lay and in a position wherein said member will engage the upper surface of said lay, said adjustments being arranged to permit said member to be placed in a position to stop said picker at said predetermined point.

GEORGE F. BELFORTI.
